UNITED STATES PATENT OFFICE.

THADDEUS HYATT, OF NEW YORK, N. Y., ASSIGNOR TO ELIZABETH ADELAIDE LAKE HYATT, OF SAME PLACE.

ILLUMINATING-GRATING OR PERFORATED PLATE OF METAL AND OTHER MATERIALS, AND CONSTRUCTIONS MADE THEREFROM.

SPECIFICATION forming part of Letters Patent No. 236,817, dated January 18, 1881.

Application filed December 24, 1880. (No model.) Patented in England October 18, 1873, and March 4, 1874.

To all whom it may concern:

Be it known that I, THADDEUS HYATT, of the city, county, and State of New York, have invented certain new and useful Improvements in Illuminating-Gratings or Perforated Plates of Metal and other Materials, and in Constructions Made Therefrom, with reference to fire-proofing and ornamenting the same, of which the following is a specification.

10 The object of my invention is to make fire-proof illuminating roofs and surfaces and roof-pavements or area-coverings by constructing them of materials fire-proof in themselves or of materials made fire-proof.

15 The illuminating roofs, surfaces, and area-coverings now in general use throughout the country are constructions devised by me as an application to new and useful purposes of my original invention of an illuminating-grating or perforated metal plate set with glass, patented by me as a vault-cover or coal-hole plate in the year 1845; as invented by me in the year 1834. These constructions are made of naked metal, and consequently are not 25 strictly fire-proof, although incombustible.

20 My present invention is the application of strictly fire-proof illuminating-gratings or perforated plates set with glass to the construction of illuminating-roofs, walking and other 30 surfaces, and embraces the following novel points, to wit: First, fireproofed illuminating-gratings where glasses previously inclosed in mounts or jackets enter into the combination; second, glasses applied (either nakedly

35 or set in mounts) to fireproofed metal gratings or plates after the fireproofing material has become set and hard; third, applying molded and hardened fireproofing materials to glass-set metal gratings or plates; fourth, 40 ornamental fire-proof illuminating-surfaces formed of the above-named construction materials; fifth, glass-set mounts in the form of common bricks, and constructions therefrom made in the manner of ordinary brick con- 45 structions.

45 The illuminating construction patented by me in England in 1869 as a "beam-platform," made of illuminating-gratings faced with asphalt, was fire-proof to the extent that as-

phalt is a fire-proof material and to the extent that the application of the material to one surface only could make it, but by reason of its coating became possessed of three qualities not existing in my previous structures—viz., first, fire-proof within the limits above 50 stated; second, non-sweating to the extent of the covered surface; third, non-slipping. The concrete employed in the 1869 construction was a bituminous one.

55 My present improvements have reference to obtaining the above-named three qualities in better shape by employing hydraulic cements, concretes, and baked clays, the invention consisting in making glass-set gratings of baked clays, or of Portland or other hydraulic cement, concrete, or material possessing hydraulic properties, or of glass-set metal gratings incased in fire-proofing material, and in 60 constructions made therefrom, the novel features of the constructions being, first, a continuous surface of the incasing material, and on both the weather and house face of the roof or surface; second, in addition to the fire-proof quality, obtaining, as a result of covering both surfaces of the construction, security 65 against the wrenching strains that now affect illuminating-roofs and roof-pavements covered with concrete or material on the weather-face only, where the naked metal of the under side is expanded by the hot atmosphere below it 70 at a moment when the concrete or material without is feeling the effects of a winter's freezing cold.

75 The aforesaid improvements were secured to me in England by Patents No. 3,380, October 18, 1873, and No. 783, March 4, 1874. In the former the invention is described in the form of cells and cell-quarries, the roofs or constructions formed by their union being honey-combed. In the latter the invention is 80 described in the form of the ordinary illuminating-gratings or perforated metal plates in common use, the fireproofing materials employed to cover them consisting of baked clays or brick in plain and ornamental shapes, also 85 fire-clay combined with asbestos and gelatinous silica, also hydraulic cements and concretes, employed and applied either according 90 95

to the ordinary and common methods of applying plastic materials or in a molded and hardened state, the union of any number of such incased gratings producing roofs and surfaces 5 with fire-proof junction-edges, and consequently complete fire-protection, because of the continuous fire-proof surface of the structure so formed.

In the drawings attached hereto, and making part of this specification, like parts are indicated by like letters in all the figures.

Figure I represents an illuminating-cell, A, a a being the top or weather face; b b, the sides; c c, the glasses. The cell is made of 15 metal incased in fireproofing material, (represented by the dotted surface.) d d is a portion of the metal left exposed.

Fig. II represents a cell-quarry holding seven glasses.

Fig. III represents the union of a number of 20 such cell-quarries as employed to form roofs and surfaces.

Fig. IV represents a cast-iron grating, B, made with square light-holes, incased, like the 25 cells, with fireproofing material. The light-holes are represented as set some with square glasses c c and others with circular glasses set in square mounts.

Fig. V represents three of such incased gratings joined by abutting them together, the fire-proof incasement of one grating being in 30 this way brought into contact with the adjoining one, thus forming one continuous surface of fireproofing material over the entire 35 roof or structure, as well upon the under as the upper face thereof. C represents a circular ornamental mount inclosing a circular glass. D represents an octagon mount inclosing a circular glass. E represents a hexagon mount 40 inclosing a circular glass, and F represents a mount made of ordinary brick material in brick form, containing three glasses, and designed for being laid with other bricks, either illuminating or otherwise, in wall, partition, roof, and 45 floor constructions requiring light.

Fig. VI represents an illuminating-grating where the glasses are inclosed in ornamental circular mounts, like C.

Fig. VII represents an illuminating-grating 50 where the glasses are inclosed in octagon mounts, like D; and Fig. VIII represents an illuminating-grating where the glasses are inclosed in hexagon mounts, like E. I prefer to make the mounts of colored baked clays, such 55 as tessellated or Minton pavements are made of. They may be combined in the manner of making such pavements, or according to the plan described, and illustrated by Fig. 19, in my American Patent No. 206,332, July 23, 60 1878, where concrete surfaces are made in ornamental and design form by means either of glasses (when light is an object) made in ornamental shapes, or (where no light is wanted) by means of colored bricks in ornamental shape, 65 the contour of the glasses or bricks expressing the design in the concrete forming the surface between them, the difference between the Min-

ton pavement and mine being that in place of joining the colored bricks or tiles closely, with only room enough for the cementing material, 70 I place them farther apart, so as to make the concrete cementing body itself form a portion of the design surface.

Figs. IV and V represent incased gratings where a portion of the glasses are shown as set 75 nakedly in square shape, and others of circular shape are set in square mounts to fit the openings of the grating. The gratings here shown are meant to represent the invention as described in my English Patent No. 783, 1874, 80 where the glasses are "set directly" (nakedly) "in the openings as left after the gratings have been incased; or they may be first set in brick mounts, and these mounts be then joined to the incased grating by hydraulic cement." 85

Fig. IX represents, in cross-section, such a grating where the incasement has been put about the metal in the condition of a plastic material or concrete and allowed to set and harden before joining the glasses to it, the 90 glasses, whether naked, as represented in the figure, or set in brick mounts, as mentioned in the English patent, being then let into the apertures and there fixed by means of hydraulic cement.

Fig. X represents, in cross-section, the same thing as Fig. IX, except that the fireproofing material, instead of being put about the metal in plastic condition, is first molded and hardened, or, if made of baked clay, is then in the 100 form of terra-cotta or brick sections e e, which embrace the bar of the grating d on either side.

Where the gratings are incased by the method represented by Fig. X, it is evident 105 that the glasses, whether naked or in mounts, must be joined to them after the incasement has been put on. It is also evident that where the material is put about the grating in a plastic state and allowed to set and harden, as intended to be represented by Fig. IX, the glasses, whether naked or set in mounts, require to be united by hydraulic cement to the incased grating.

Figs. XI and XII illustrate a mode of incasing the grating, with the glasses, whether naked or in mounts, placed in the openings of the grating before the application of the incasing material, whether in a plastic state or in a molded and hardened one.

Fig. XI represents the plastic method of incasement, the process being interrupted when half finished.

Fig. XII represents the dry method of molded sections. It is seen that the incasement, 125 whether plastic or hard, can be as easily applied with the glasses in position as not, and whether set in mounts or nakedly, the method of setting being the same in both cases.

Having thus fully described and illustrated 130 my invention, what I claim, and desire to secure by Letters Patent, is—

1. Illuminating-gratings or perforated metal plates set with glasses, in combination with a

fire-proof incasement which completely incloses the metal, substantially as and for the purposes herein set forth, and illustrated by my drawings.

5. Illuminating-roofs and walking-surfaces made by the combination of any number of fireproofed illuminating gratings or plates, as aforesaid, substantially as and for the purposes herein set forth, and illustrated by my drawings.

10. Illuminating-roofs and walking-surfaces made by the combination of any number of fireproofed gratings or plates, as aforesaid, so combined as to produce a practically continuous fire-proof roof and walking-surface, substantially as and for the purposes herein described, and illustrated by my drawings.

15. Illuminating-roofs and walking-surfaces formed by the combination of any number of illuminating-gratings or perforated metal plates overlaid by or incased with ornamental fireproofing materials, substantially as and for the purposes herein set forth, and illustrated by my drawings.

5. Illuminating-roofs and walking-surfaces 25 formed by the combination of any number of illuminating-gratings or perforated metal plates overlaid by or incased with fireproofing materials in which the glasses are inclosed in jackets or mounts, substantially as and for 30 the purposes herein set forth, and illustrated by my drawings.

6. Applying fireproofing material in molded and hardened form as an overlayer or as an incasement to illuminating-gratings or perforated metal plates, substantially as and for 35 the purposes herein set forth and illustrated by my drawings.

7. Applying the glasses of illuminating gratings or plates, when overlaid by or incased in 40 fireproofing material, after the same has become set and hard, substantially as and for the purposes herein set forth, and illustrated by my drawings.

THADDEUS HYATT.
